UNITED STATES PATENT OFFICE.

SAMUEL WILLIAM WANATIK, OF DETROIT, MICHIGAN.

KNIFE SHARPENER.

Application filed November 5, 1925. Serial No. 67,058.

The object of the invention is so to construct the body of a knife sharpener that an efficient sharpening edge will be provided, novel means being supplied for holding the knife or other article to be sharpened, in proper relation to said edge.

It is within the province of the disclosure to improve generally and to enhance the utility of devices of that type to which the invention appertains.

With the above and other objects in view which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

In the drawings:

Figure 1 shows in elevation, a device constructed in accordance with the invention, parts being in section, and parts being broken away; Figure 2 is a section on the line 2--2 of Figure 1.

The device forming the subject matter of this application comprises a body 1 made of any desired abrasive material, the body 1 being broken away in Figure 1, to indicate that the body may be of any preferred length. The body 1 has longitudinal grooves 2, each groove being formed by a plane wall 3 and a concaved wall 4, the concaved wall defining a sharpening edge 5 at the periphery of the body 1. The body 1 has a flat longitudinal surface 6 terminated at the outer edge of the plane wall 3 and disposed opposite to the sharpening edge 5. Owing to the provision of the flat surface 6, a knife or other article may be held in proper position so that it will be sharpened upon the edge 5, when the knife is drawn along the body 1. After the knife has been sharpened, to approximately the desired condition, the sharpening job may

be finished by drawing the knife along the rounded part 7 of the periphery of the body 1. As shown at 8, the body 1 tapers toward its free end, and, as indicated at 9, the grooves 2 and the flat surface 6 diminish in width as they extend toward the outer end of the body 1.

The device comprises a handle 10 having a shank 11 which is threaded into the wider end of the body 1, although any suitable means may be provided for mounting the handle on the body 1. At the outer end of the handle 10 there is a ring 12 or any other suitable means whereby the tool may be hung up when not in use.

In order to guard the hand of an operator, an outstanding washer 15 is mounted on the shank 11 of the handle 10 and is bound between the end of the handle and the end of the body 1.

What is claimed is:

1. A sharpener of the class described, comprising a body having a longitudinal groove formed by plane and concaved walls, the concaved wall defining a longitudinal sharpening edge at the periphery of the body, the body having a flat longitudinal surface terminated at the outer edge of the plane wall and disposed opposite to the sharpening edge.

2. A sharpener of the class described, comprising a body having a longitudinal groove formed by plane and concaved walls, the concaved wall defining a longitudinal sharpening edge at the periphery of the body, the body having a flat longitudinal surface terminated at the outer edge of the plane wall and disposed opposite to the sharpening edge, the body tapering toward one end, and the groove and the flat longitudinal surface diminishing in width toward said end of the body.

In testimony that I claim the foregoing as my own, I have hereto affixed my signature.

SAMUEL WILLIAM WANATIK.
